Primary Examiner—Ian Simmons(74) **Attorney, Agent, or Firm**—Ohlandt, Greeley, Ruggiero & Perle, LLP(57) **CLAIM**

The ornamental design for a nipple, as shown and described.

DESCRIPTION

FIG. 1 is a perspective view of a nipple, showing my new design;

FIG. 2 is a front view of the nipple of FIG. 1; and,

FIG. 3 is a top view of the nipple of FIG. 1.

The broken line showing in FIGS. 1 through 3 is for illustrative purposes only and forms no part of the claimed design.
